UNITED STATES PATENT OFFICE.

WALDO A. RICH, JR., OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS.

PAPER DECORATION.

1,248,916.

Specification of Letters Patent. Patented Dec. 4, 1917.

Application filed July 19, 1917. Serial No. 181,524.

To all whom it may concern:

Be it known that I, WALDO A. RICH, Jr., a citizen of the United States, and resident of Framingham, in the county of Middlesex and State of Massachusetts, have invented new and useful Improvements in Paper Decorations, of which the following is a specification.

This invention relates to paper decorations or "paper garlands" as they are commonly called of the general class shown in U. S. Patent to Burger No. 603,619, comprising essentially end members with sheets or layers of tissue paper therebetween, the 10 said garland being adapted to be folded into package form and to be extended for decorative display.

These garlands are peculiarly adapted and intended for use as decorations upon 20 particular festival days such as Christmas, St. Valentine's day, Hallowe'en, etc., all of which have a recognized and characteristic emblem such as holly for Christmas, hearts for St. Valentine's, jack-o'-lanterns for Hallowe'en, etc.

In the manufacture and sale of these garlands it has long been recognized as highly desirable, if not indeed commercially essential, that the garlands should not only be of 30 appropriate colors but should also display the characteristic emblem of the particular festival day for which they are intended. Garlands made under and in accordance with the Burger patent are adapted to display a 35 mass of color only, and therefore it has been customary in the sale of these garlands to attach thereto the characteristic emblem of the particular day, these emblems being commonly made of card board or other relatively 40 stiff material suspended at intervals throughout the length of the garland.

Garlands thus made in which the emblems are additions merely to the otherwise complete structure, are relatively expensive 45 and in many instances not wholly satisfactory from an artistic point of view. Nor does this method of garland making result in a decoration wherein the characteristic emblem of the day is, as it should be, the 50 striking and salient feature of the design. Not only are the suspended emblems necessarily relatively few in number and therefore subordinate to the form and mass of color provided by the body of the garland, 55 but being flat and attached to the tissue

paper layers, an edge view only thereof is obtained when the garland is viewed from the front.

It is the object of this invention to provide a garland wherein the tissue paper layers of which the body is formed may themselves be made in shapes or figures appropriate to and characteristic of a particular festival day or provided with such shapes or figures upon their exposed faces 60 so that such shapes or figures become the salient and dominant element of the garland design.

Referring to the drawings which illustrate certain embodiments of my invention, 70

Fig. 1 is a perspective view of the garland in folded or package form;

Fig. 2 is a perspective view of the extended garland;

Fig. 3 is a plan view of the garland shown 75 in Fig. 2;

Fig. 4 is a plan view of one of the bases;

Fig. 5 is a view similar to Fig. 2, showing an alternative form.

My improved garland consists of ends 80 or bases A and B preferably of relatively stiff cardboard or similar material, between which are layers or sheets C preferably of tissue paper or like material. The said bases and paper sheets are of the same 85 shape, which may be any shape desired, as for example conventional heart-shape, as shown, to provide a garland adapted and intended for use as a decoration on St. Valentine's day.

The body of the garland is made in connected sections, each section comprising a plurality of sheets C. In the preferred form of the invention shown in the drawings there are four such sheets, each sheet 90 provided upon one edge with a relatively long tab D located above the center of gravity of the sheet and upon its opposite edge with a relatively short tab E. The tab D of one sheet is secured to the tab D of the 100 adjacent sheet, and the tabs E of adjacent sheets are likewise secured together. The tabs D adjacent to the bases A and B respectively, are secured thereto, and the tabs D of adjacent sections are secured together, 105 thus providing a unitary collapsible garland.

Preferably a suitable adhesive is employed for securing the tabs to one another, and the sheet material adjacent to the tabs is 110

weakened as by substantially vertical slots *d* and *e* which define the bend and permit the paper sheets readily to swing without undue strain upon the connected tabs.

5. The flexible supporting member *F*, preferably a string, passes through the bases *A* and *B* and through the center of the attached tabs *D* so that said string is thus disposed above the center of gravity of the 10 sheets, insuring their upright position and proper display.

It will be clear that because of the edge connections between the sheets provided by their attached tabs, said sheets swing on a 15 vertical bend flatwise into view so that not only the shape of the sheets but their entire faces are visible when the garland is extended and hung for display. Therefore, the 20 sheets may not only be of any desired shape and color appropriate to a particular festival day but may be printed or otherwise decorated upon their faces with attractive and appropriate designs, enhancing the 25 beauty of the garland and its adaptability for use upon the particular occasion.

It is further to be observed that the shapes or designs employed are not necessarily limited to a single sheet *C* or to decoration upon a single sheet. For example, in Fig. 5 the 30 adjacent sheets *C'* are cut to form a butterfly and the design is symmetrically disposed on two adjacent sheets.

The method of manufacture is to superpose the sheets *C* between their bases *A* and 35 *B* with the adhesive applied at the proper places, and then by a die or other suitable mechanism to cut the entire garland in the desired shape at a single operation. It will therefore be clear that the sheets *C* need not 40 necessarily be all of the same shape as shown in the drawings; but by provision of a suitable die all the sheets upon one side of the line *x*—*x*, Fig. 4, may be of one shape and those upon the other side of an entirely different shape. Thus when a particular day 45 has more than one characteristic emblem, such as the figures of jack-o'-lanterns and witches for Hallowe'en, both may be incorporated in the same garland, which will 50 have an entirely different appearance when viewed from opposite sides.

I claim:

1. A collapsible garland comprising a plurality of sheets arranged in series, each sheet 55 being centrally connected to the next adjacent sheet in one direction and being connected to the next adjacent sheet in the opposite direction at points disposed on opposite sides of the central connection, and the 60 sheets being free to swing on a vertical bend

flatwise into view when the garland is extended.

2. A collapsible paper garland comprising paper sheets and a flexible supporting member disposed above the center of gravity 65 of said sheets, said sheets connected at their edges in such manner as to swing on a vertical bend flatwise into view when the garland is extended.

3. A collapsible paper garland formed in 70 attached sections, each section comprising paper sheets connected at their edges in such manner as to swing on a vertical bend flatwise into view when the garland is extended, and a supporting member passing 75 through the attached portions of said sections.

4. A collapsible garland comprising a plurality of sheets arranged in series and connected together at points above the center of 80 gravity of the sheets, said sheets being connected at their edges in such manner as to swing on a vertical bend flatwise into view when the garland is extended.

5. A collapsible paper garland formed in 85 sections, each section comprising paper sheets having tabs disposed above the center of gravity of the sheets, tabs of one section being secured to tabs of the adjacent section, and a flexible supporting member passing 90 through said secured tabs.

6. A collapsible garland formed in sections, each section comprising sheets having supporting tabs disposed above the center of gravity of the sheets and the tabs of adjacent sections being connected together, whereby the sheets will hang substantially 95 vertically from said supporting tabs when the garland is extended.

7. A collapsible garland comprising a plurality of sheets arranged in series, the sheets being connected to each other at the center of the garland and at two sides of the garland and being free to swing on vertical 100 bends flatwise into view when the garland is extended, and the sheets having weakened 105 portions in the region of said bends to facilitate the bending.

8. A collapsible garland comprising a plurality of sheets arranged in series, the sheets 110 being connected to each other at the center of the garland and at two sides of the garland and being free to swing on vertical bends flatwise into view when the garland is extended, and the sheets having slots in 115 the region of said bends to facilitate the bending.

Signed by me at Framingham, Massachusetts, this tenth day of July, 1917.

WALDO A. RICH, JR.
